US00D564111S

(12) **United States Design Patent** (10) **Patent No.:** **US D564,111 S**
Hillard (45) **Date of Patent:** **** Mar. 11, 2008**

(54) **HEADLAMP**

(75) Inventor: **Jake L. Hillard**, Wichita, KS (US)

(73) Assignee: **The Coleman Company, Inc.**, Wichita, KS (US)

(**) Term: **14 Years**

(21) Appl. No.: **29/246,844**

(22) Filed: **May 15, 2006**

(51) **LOC (8) Cl.** **26-02**

(52) **U.S. Cl.** **D26/39**

(58) **Field of Classification Search** D26/37, D26/38, 39, 51, 46; 362/103, 105, 106, 107, 362/108, 157, 158, 183, 184, 190, 191, 196, 362/197, 198, 208, 804

See application file for complete search history.

(57) **CLAIM**

The ornamental design for a headlamp, as shown and described.

DESCRIPTION

FIG. 1 is a side perspective of the first embodiment of my new headlamp;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a side perspective of the second embodiment of my new headlamp;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken line showing is for illustrative purposes only and forms no part of the claimed design.

1 Claim, 8 Drawing Sheets
